ICE REMOVING COVERING FOR AIRFOILS

Robert G. Campbell, Cuyahoga Falls, Ohio, assignor to The B. F. Goodrich Company, New York, N. Y., a corporation of New York

Application March 17, 1944, Serial No. 526,866

6 Claims. (Cl. 244—134)

1

This invention relates to protective coverings or apparatus for airfoils and especially to inflatable coverings for preventing the accumulation of ice on the leading edge of such airfoils.

Objects of the invention are to provide effectively for breaking and removing ice formations on the leading edge of an airfoil; to provide for moving laterally pieces of broken ice into the ambient airstream for removal by the latter; to provide for expanding a protective covering or apparatus along an element thereof extending diagonally across the leading edge; to provide for local expansion of such diagonal element; to provide for expanding a central zone of the covering along one or more sinuous paths extending spanwise along and across the chord line of the leading edge; and to provide simplicity of construction, convenience of manufacture and effectiveness of operation.

These and other objects and advantages of the invention will be apparent from the following description.

In the accompanying drawings which form a part of this specification and in which like numerals are employed to designate like parts throughout the same,

Fig. 1 is a perspective view of protective apparatus having a plurality of sinuous inflatable tubes installed on the leading edge of an airfoil, parts being broken away and in section,

Fig. 2 is a plan view from above of a modified construction of the protective covering shown in Fig. 1, before mounting on the airfoil, parts being broken away,

Fig. 3 is a view like Fig. 2 showing another modification of the protective covering, and

Fig. 4 is a perspective plan view from above of a further modification of the protective covering, parts being broken away and in section.

In an embodiment of the invention illustrated in Fig. 1 a protective apparatus 10 includes a body or covering 11 of resilient rubber or other rubber-like material mounted at the leading edge of an airfoil 12 such, for example, as a wing of an aircraft. The covering 10 is constructed and arranged to provide a substantially smooth aerodynamic contour around the leading edge for maintaining the aerodynamic characteristics of the airfoil. The body 11 may be adhered throughout the extent of its inner surface 13 to the skin of the airfoil 12 or may be attached in a suitable manner as by screw fasteners (not shown) at its upper and lower attaching margins 14 and 15, respectively. For the latter arrangement of attachment, the covering is mounted in a condition of

2

stretch between the margins 14, 15 to hold the covering against the airfoil when not in operation.

The rubber body or covering 11 has embedded therein a pair of adjacent inflatable tubes or elements 16 and 17 curved uniformly about the chord line 18 of the leading edge and 180° out of phase relative to each other, the tubes having walls of suitable resilient rubber-like material. The tubes are arranged in an overlapping manner and each 10 extends spanwise in a sinuously curved path along the leading edge and across the chord line 18, the tubes 16, 17 being in overlying relation at spaced-apart regions where they diagonally cross the chord line.

15 It is desirable that the inflatable tubes 16, 17 be disposed adjacent the outer surface of the covering 11 and have walls of considerable stretchability. Such walls may include in the rubber thereof reinforcing material such as stockinette 20 or other knitted or otherwise stretchable fabric, preferably of nylon or rayon, although cotton or other suitable material may be used. The stockinette fabric is stretchable both circumferentially and longitudinally of the tube, which permits 25 extensive stretching of the tube wall for expanding the cover locally at the tube zone 20 to break and loosen the ice thereon for removal by the ambient airstream. However, the reinforcing material in the walls of the tubes 16, 17 may, if 30 desired, be of substantially inextensible material such, for example, as square-woven, straight-laid fabric for imparting stretching force to adjacent rearward portions of the covering 10 upon inflation thereof.

35 The inflatable tubes 16, 17 have curved portions or reaches 21, 22 and 23, 24 extending diagonally back and forth across the chord line of the leading edge, and have their adjacent margins at separated positions as at 25, 26, and 27, 28 and 40 29, 30, disposed relatively close to the chord line, which arrangement provides for cracking and breaking the ice formation diagonally across the chord line at the region of the portions 21, 22, 23 and 24. Such a cracking action, upon inflation 45 of the tubes 16, 17 promotes a lateral shifting movement of the broken ice along the curved portions 21, 22 and 23, 24 relative to and about the chord line whereby the airstream flowing across the covering 10 acts upon the exposed surfaces 50 of the broken and loosened ice particles to further loosen such particles for their removal by the airstream.

The fabric and rubber parts of the covering are united by vulcanization and heat under pressure.

55 In the operation of the protective covering 10,

when such covering is provided with inflatable tubes 16, 17 having highly stretchable walls, the two tubes may be inflated in a cyclical manner individually or simultaneously and may be inflated through suitable connector and conduit means in communication with such tubes at one end thereof and with a suitable source of air under pressure which may be located within the body of the aircraft, for example. These tubes then distend outwardly to a substantially semi-circular shape in cross-section as shown by broken lines at 31 and 32 in Fig. 1, the walls of such tubes stretching locally to a relatively great extent within themselves by virtue of the stretchable action of the nylon fabric. Opposite loop portions 34, 35, 36 and 37 of these sinuous tubes at the regions of reverse curvature tend, upon inflation, to spread apart due to the curvature of the leading edge, which spreading action coacts with the cracking action of the tubes at the diagonally extending curved portions 21, 22, 23 and 24 to provide the desired lateral movement of the broken ice formation along the latter portions for its removal by the ambient airstream. When the tube 16, for example, is inflated, the central tube zone 20 is expanded along the sinuous path of such tube back and forth across the chord line of the leading edge and the outer portion of the rubber body 11 overlying such tube 16 is stretched extensively with little or no stretching force upon the adjacent portions rearwardly of this tube 16. A similar stretching and expanding action occurs upon inflation of the sinuous tube 17. The local stretching of these tubes 16, 17 is found to be highly effective, especially at the immediate leading edge region, in cracking and loosening the ice formation, which cracking occurs in reaches diagonally of the chord line of the leading edge rather than parallel thereto. Parts of the broken ice are moved laterally relative to and about the chord line for action thereon by the ambient airstream. In this manner such ice formation upon the covering is removed promptly and thoroughly, especially throughout the extent of the central tube zone 20.

When the protective covering 10 is provided with inflatable tubes 16, 17 having walls of substantially inextensible fabric, the covering is mounted in a condition of stretch between attaching margins 14, 15 as described hereinabove, and the tubes 16, 17 may be inflated in a cyclical manner individually or simultaneously. By virtue of the relatively inextensible walls of the tubes 16, 17, these tubes, when inflated, distend outwardly and assume an expanded condition having lesser sharpness of curvature than that of the semi-circular shape obtained when the tubes have walls of highly stretchable fabric. Upon inflation of such tubes, they expand the covering at the central tube zone 20, cracking the ice formation thereon in reaches diagonally of the chord line of the leading edge and along the sinuous paths back and forth across such chord line, and moving portions of the ice laterally relative to the chord line for removal by the flow of air. This action is also effective in imparting stretching force to and moving outwardly from the airfoil the adjacent rearward portions of the covering 10 to break and loosen the ice formations on the latter portions. In this manner the covering is expanded along overlapping sinuous paths spanwise throughout the central zone 20, and the rearward portions adjacent the tubes are stretched a substantial extent whereby the ice formations thereon are cracked and broken

for the thorough and prompt removal of such ice by the flow of air across the covering.

The modified construction of the protective covering 40 of suitable resilient rubber-like material is constructed and arranged in a manner similar to that of the protective covering 10 except that a single tube 41 is disposed in a sinuous path extending spanwise back and forth across the chord line 18 of the leading edge, which tube 10 41 may be inflated by a suitable conduit and connector means 42 in communication therewith at an end of the protective covering. The rubber walls of the tube 41 may include reinforcing material of substantially inextensible fabric for stretching rearward portions of the covering 40 or may include highly stretchable fabric like nylon stockinette fabric therein for local stretching of the covering along the sinuous path of the tube. For the arrangement shown in Fig. 2, the tube 41 is not continuously curved relative to the chord line 18 but comprises substantially straight portions or reaches 43, 44, 45 extending diagonally across the chord line and at an angle of inclination with respect to such chord line 18, adjacent straight portions 43, 44 being opposingly inclined relative to each other. The chordwise extent of the covering included within the central tube zone is such as to make possible the desired twisting and lateral shifting movement 30 diagonally across the chord line 18 of parts of the ice formation upon the breaking and cracking thereof due to the inflation of tube 41 thereby facilitating the action of the ambient airstream in further loosening and removing the broken 35 pieces of ice. The operation of the covering 40, when installed on the leading edge of the airfoil, is substantially as described hereinabove for the covering 10.

If desired, two or more tubes of the formation 40 of Fig. 2 may be arranged together in 180° phase relationship or in other desired relationships.

For the modified construction of the protective covering 50 of suitable resilient rubber-like material shown in Fig. 3, one or more tubes 51, 52 extending back and forth across the chord line 18 in a sinuous path may be provided and may be inflated by suitable conduit and connector means 53 in communication therewith. These tubes 51, 52 are embedded in the rubber body of the protective covering in the manner described hereinabove for the protective covering 10 and the rubber walls thereof may include reinforcing material of suitable substantially inextensible fabric or of suitable highly stretchable fabric. The tube 51 has straight portions or reaches 54, 54 extending diagonally across the chord line 18 and at an angle of inclination relative to such chord line, and includes straight portions 55, 55 extending chordwise substantially normal to the chord line 18, adjacent inclined portions and adjacent normal portions being generally parallel.

The provision of two tubes as in the embodiment of Fig. 3 makes possible various phase relationships, as desired. For example, the two tubes 65 may be arranged in phase, 90° or 180° out of phase, or in other desired arrangements, and one tube may be in the same formation as the other tube or it may be inverted with respect to the first tube.

The tubes 51 and 52 may be inflated individually in a cyclical manner or may be inflated simultaneously for providing the desired breaking and loosening action on the ice formation on the covering 50. Upon inflation of the tube 51, for example, the ice is cracked along the

sinuous path of the tube, and along the inclined straight portions 54, 54 the cracked ice is shifted laterally by virtue of inflation of such tube 51 as described hereinabove for the covering 10.

In the embodiment of Fig. 4, a protective covering 60 of suitable resilient rubber-like material includes inflatable tubes 61, 62 disposed in the central tube zone 63 between attaching margins 64 and 65 and includes stretchable portions 66 and 67 extending rearwardly from the central zone 63, such stretchable portions having spaced-apart apertures 70, 70 extending therethrough for venting the covering 60. The attaching margins 64 and 65 include therein reinforcing strips 68, 68 of suitable relatively inextensible fabric material folded about metal bead elements 69, 69.

The covering 60 is mounted on the airfoil in a condition of stretch between the attaching margins 64 and 65 as by suitable screw fasteners (not shown) extending through the rubber material and the reinforcing strips 68, 68 inwardly of the bead elements 69, 69. An offset arrangement is provided for mounting a fairing strip (not shown) for facilitating smooth flow of air across the covering at such margins.

The inflatable tube 62 having a wall of suitable resilient rubber-like material includes in such wall expansion-limiting reinforcement of suitable substantially inextensible fabric material and such tube is embedded in the rubber covering 60 desirably adjacent the inner surface thereof. The tube 62 is disposed centrally about the chord line 18 and extends in a straight path along such chord line. When the tube 62 is inflated and distended outwardly, it assumes a generally rounded form in section which action moves the stretchable portions 66 and 67 outwardly from the airfoil and imparts stretching force to the portions 66, 67, effectively breaking and loosening the ice thereon for thorough and prompt removal by the flow of air over the covering.

The tube 61 has a wall of suitable resilient rubber-like material and includes therein highly stretchable nylon stockinette fabric. The tube 61 may be superimposed upon the tube 62 adjacent the outer surface of the covering 60. Such tube 61 extends along the central tube zone 63 in a sinuously curved path back and forth diagonally across the chord line 18 of the leading edge. As described hereinabove for the covering 10, when the tube 61 is inflated, the protective covering 60 is expanded locally at the central zone 63 along the sinuous path of such tube 61 breaking and loosening the ice formation along the latter tube and providing the desired lateral shifting movement of the broken pieces of ice into the path of the ambient airstream whereby such pieces are thoroughly and promptly removed.

In the operation of the covering 60 the inflatable tube 61 is inflated first for locally expanding such covering at the central zone and facilitating the effective removal of the ice formation immediately at the leading edge along the chord line 18. The tube 61 is then deflated and the tube 62 is next inflated, which action further promotes removal of any remaining pieces of ice at the central zone 63 and stretching the stretchable portions 66, 67 for cracking and breaking the ice formation thereon for removal by the ambient airstream. If desired, the two superimposed tubes 61, 62 may be inflated simultaneously.

The tube arrangements and formations herein described may be utilized alone in a covering or may be associated with one or more other tubes in adjacent or superimposed relations, as desired.

Variations may be made without departing from the scope of the invention as it is defined in the following claims.

I claim:

1. Apparatus for preventing the accumulation of ice on the leading edge of an airfoil, said apparatus comprising a covering for said leading edge comprising resilient rubber-like material having an inflatable tube extending along the covering and throughout the width of its bore diagonally across a substantially straight line along the covering with a portion of said tube throughout the width of its bore disposed entirely to one side of and spaced from said line and with another portion of said tube throughout the width of its bore disposed entirely to the other side of and spaced from said line, said covering being constructed and arranged to present upon inflation of said tube a distended surface of the covering substantially coextensive with the width of said tube throughout its extent.
2. Apparatus for preventing the accumulation of ice on the leading edge of an airfoil, said apparatus comprising a covering for said leading edge comprising resilient rubber-like material having an inflatable tube extending in a sinuous path along the covering crossing and recrossing a substantially straight line along the covering at spaced-apart positions along said line with portions of the tube throughout the width of its bore disposed entirely to one side of and spaced from said line and with other portions of the tube throughout the width of its bore disposed entirely to the other side of and spaced from said line, said covering being constructed and arranged to present upon inflation of said tube a distended surface of the covering substantially coextensive with the width of said tube throughout its extent.
3. Apparatus for preventing the accumulation of ice on the leading edge of an airfoil, said apparatus comprising a covering for said leading edge comprising resilient rubber-like material having an inflatable tube including stretchable fabric material in the wall thereof for local stretching of said covering and extending in a sinuous path spanwise along the covering crossing and recrossing a substantially straight spanwise-extending line of the covering at spaced-apart positions along said line with portions of the tube throughout the width of its bore disposed entirely to one side of and spaced from said line and with other portions of the tube throughout the width of its bore disposed entirely to the other side of and spaced from said line, said covering being constructed and arranged to present upon inflation of said tube a distended surface of the covering substantially coextensive with the width of said tube throughout its extent.
4. Apparatus for preventing the accumulation of ice on the leading edge of an airfoil, said apparatus comprising a covering for said leading edge comprising resilient rubber-like material having a plurality of inflatable tubes in superimposed relation to one another extending along the covering, at least one of said tubes extending in a sinuous path along the covering crossing and recrossing a substantially straight line along the covering at spaced-apart positions along said line in overlapping relation with another of said tubes

at said positions and with portions of the sinuous tube throughout the width of its bore disposed entirely to one side of and spaced from said line and with other portions of said sinuous tube throughout the width of its bore disposed entirely to the other side of and spaced from said line, said covering being constructed and arranged to present upon inflation of said sinuous tube a distended surface of the covering substantially coextensive with the width of such tube throughout its extent.

5. Apparatus for preventing the accumulation of ice on the leading edge of an airfoil, said apparatus comprising a covering for said leading edge comprising resilient rubber-like material having a pair of inflatable tubes in superimposed relation to one another each extending in a substantially continuously curved sinuous path spanwise along the covering crossing and recrossing a substantially straight spanwise-extending line at spaced-apart positions along said line in overlapping relation with the other tube at said positions, the portions of said pair of inflatable tubes between the crossing positions being disposed on opposite sides of and spaced from said line, and said covering being constructed and arranged to present upon inflation of each inflatable tube a distended surface of the covering substantially coextensive with the width of the tube throughout its extent.

6. Apparatus for preventing the accumulation 30

of ice on the leading edge, said apparatus comprising a covering for said leading edge comprising resilient rubber-like material having a pair of inflatable tubes in superimposed relation to one another each extending in a substantially continuously curved sinuous path spanwise along the covering crossing and recrossing a substantially straight spanwise-extending line at spaced-apart positions along said line in overlapping relation with the other tube at said positions, the portions of said pair of inflatable tubes between the crossing positions being disposed on opposite sides of and spaced from said line, and each of the inflatable tubes including stretchable fabric material in the wall thereof for local distention of the covering upon inflation of the tubes to present a curved surface of the covering substantially coextensive with the width of the tube throughout its extent.
